Ill., a corporation of Illinois

Original application November 9, 1931, Serial No.
573,738. Divided and this application Decem-
ber 26, 1931, Serial No. 583,318

4 Claims. (Cl. 274—1)

This invention relates to an improvement in phonographs and more particularly to an improved construction of means for supporting the sound box or pick-up device which receives impressions from a record.

The main object of the invention is to provide an arrangement for supporting a sound box or pick-up in such a manner that the device will be maintained in substantially constant relation, throughout its travel across the face of a record, to the record groove with which it cooperates. Another object is to provide a comparatively simple supporting means of the class above described which will not add materially to the cost of constructing a phonograph and which will not materially effect the freedom of movement of the device as an incident to its cooperation with a record. Other objects and advantages of the invention will be understood by reference to the following specification and accompanying drawing in which a portion of a phonograph including pick-up supporting mechanism of the type above referred to is shown.

This application is a division of my copending application, Serial No. 573,738, filed November 9, 1931.

In the drawing:—

Figs. 1 and 2 are fragmentary plans and Fig. 3 is a section on the line 3—3 of Fig. 2.

Referring now to the drawing, I have indicated a turntable 5 on which a record 6 of the ordinary flat disk type is positioned.

A pick-up 7 for the electrical reproduction of the record 6 is provided with a needle or stylus 8 which engages the sound groove of the record. The needle 8 may be of any suitable or preferred type and in this instance I have illustrated it as being a form of needle having a chisel point 9 which presents an elongated sharp edge to fit the record groove. This type of needle has been developed to provide a so-called permanent needle, i. e. one which is capable of playing a very large number of records. This form of needle, because of its elongated edge, requires that the pick-up member be so supported that the needle will not turn on its own axis in order that cutting action and consequent damage to the record be avoided.

For maintaining the pick-up 7 with its needle 8 in substantially constant position relative to the record groove with which it cooperates, the pick-up is provided with an extension or arm 10, which in this instance is illustrated as being an independent member secured to the pick-up device by means of a screw 11. The arm 10 is pivoted intermediate its ends as indicated at 12 to

the free end of a main supporting arm 13, which arm is mounted for swinging movement about horizontal and vertical axes at its opposite end.

The arm 13 is mounted in a frame portion 14 the said frame portion being provided with a bearing boss 15 which is suitably bored out to rotatably receive a pivot pin 16. The upper end of the pivot pin 16 is provided with a head 17 which carries an axially horizontal pivot pin 18. The arm 13 is provided with a depending lug or ear 19 suitably apertured to receive the pivot pin 18. Any desired provision may be made for maintaining the parts in the assembled relation described, and it will be seen that the arm 13 may swing horizontally about the axis of the pivot pin 15 17 and vertically about the axis of the pivot pin 18.

For controlling the adjustment of the pick-up 7 about the axis of the pivot pin 12, a lever 20 is pivoted intermediate its ends as indicated at 21 to a boss 22 which depends from the bottom side of the arm 13. One end of the lever 20 is slotted as indicated at 23 to receive a pin 24 which depends from the free end of the arm 10. The other end of the lever 20 is slotted as indicated at 25 to receive a pin 26 which is secured in fixed position in a part 27 formed integrally with the frame element 14.

In Fig. 1, the starting position of the pick-up relative to the record is shown. The needle or stylus 8 is then in engagement with the outer end of the record groove. The pick-up device is then disposed in such a position that the elongated edge of the needle is on a tangent to the record groove at the point then engaged by the needle. As an incident to the rotation of the record, the pick-up and needle are caused to travel inwardly across the face of the record, and it will be seen that such travel is permitted by reason of the horizontal swinging ability of the main supporting arm 13. However, as an incident to horizontal swinging movement of the arm 13, the lever 20 is also caused to swing on its pivot 21 by reason of its engagement at one end with the fixed pin 26. The opposite end of the lever 20 serves to impart independent swinging movement of the pick-up on its pivot 12, in a direction reverse to that of the arm 13, with the result that the pick-up and its needle are maintained in substantially constant relation to the record groove.

Vertical swinging movement of the pick-up is permitted about the axis of the pivot 18 so that the pick-up may be lifted from the inner end of the record groove either automatically or me- 55

chanically and swung back to its initial position as illustrated in Fig. 1.

In the case of a pick-up for the electrical reproduction of records, the arm 13 may be suitably drilled or hollowed out to constitute a conduit for the necessary conductor 28, and in the case of a sound box wherein the vibrations of the record groove are mechanically reproduced, the arm 13 may be in the form of a tone arm in accordance with more or less conventional practice, suitable provisions being made for adjustably connecting the sound box and tone arm.

Changes in the above described construction may be made without departing from the spirit of the invention, the scope of which should be determined by reference to the following claims, the same being construed as broadly as possible consistent with the state of the art. In the following claims I have used the terms "pick-up" and "reproducer" in a broad sense, to include both a mechanical and electrical reproducer.

I claim as my invention:—

1. In a phonograph having a turntable, a pick-up having means for engaging the sound groove of a record carried by turntable, means for mounting said pick-up so as to maintain the same in substantially constant, predetermined relation to the tangent of a record sound-groove during the normal travel of the pick-up across the face of the record, said means comprising a supporting arm pivotally mounted at one end for horizontal swinging movement, an arm secured at one end to said pick-up, projecting therefrom and pivotally mounted intermediate its ends on the free end of said supporting arm, a lever pivotally mounted intermediate its ends on said supporting arm and

having one end pivotally connected to the free end of said pick-up arm, and means engaging the other end of said lever for effecting swinging movement of said lever as an incident to the swinging movement of said supporting arm. 5

2. In a phonograph having a record holder, an arm mounted at its outer end to swing horizontally and vertically above the record holder, a reproducer vertically pivoted on the inner free end of said arm, a lever pivotally mounted on the supporting arm to move vertically and horizontally therewith and having a pivotal connection with the reproducer, and means engaging the lever to position the reproducer during the movement of the supporting arm. 10

3. In a phonograph having a record holder, an arm mounted at its outer end to swing horizontally and vertically above the record holder, a reproducer vertically pivoted on the inner free end of said arm, a lever pivotally mounted on the supporting arm and having a pin and slot connection with the reproducer, and a stationary element having a pin and slot connection with the lever, adapted to permit the vertical movement of the lever with the reproducer supporting arm. 25

4. In a phonograph having a turntable, an arm mounted for horizontal movement above the turntable, a pick-up adjustably mounted on said arm, a lever pivotally mounted intermediate its ends on said arm, a connection between said lever and said pick-up, and means cooperating with said lever to maintain said pick-up, throughout its travel across the record, in approximately constant, predetermined relation to the record sound groove. 30
